CHESTER A. FRICK, OF MUNCIE, INDIANA, ASSIGNOR TO GLASCOCK BROTHERS MANUFACTURING COMPANY, OF MUNCIE, INDIANA, A CORPORATION OF INDIANA

STAND FOR BOTTLE DISPENSING REFRIGERATORS

Application filed May 5, 1930, Serial No. 449,711. Renewed May 7, 1931.

My invention relates to improvements in bottle dispensing refrigerators and more particularly to the stand for supporting the same.

5 It is one of the objects of my invention to provide a supporting stand particularly adaptable for supporting bottle dispensing refrigerators, which stand shall occupy a minimum of floor space, shall be cheap to manufacture and readily assembled.

10 For the purpose of disclosing my invention, I have illustrated one embodiment thereof in the accompanying drawings, in which:

Fig. 1 is an elevation partly in section of a stand embodying my invention;

15 Fig. 2 is a plan of the bottom portion of the frame;

Fig. 3 is a perspective view of the cover plate for the bottom portion of the stand.

20 In the embodiment illustrated, I provide a rectangular base frame 1 preferably formed of angle members welded together at their corners. Extending upwardly and inclined inwardly from each corner is an angle member 2, the top of each of which is secured to a top plate 3. This plate is rectangular and is provided on each side with a downturned flange 4, the top ends of the angle members 2 being welded in the corners of this flange.

25 The structure thus described forms a pyramidal bottom frame which is covered on three sides by panels 5, preferably all formed from a single sheet of material. The bottom edges of the panels are turned to lie parallel with the sides of the base frame 1 and are secured thereto by bolts or screws and the top edges of the panels are turned to overlap the top plate 3. The free edges of the cover plate forming the panels 5 are turned to

30 form flanges 6 which laps two of the angle members 2. Each of the panels is provided with an opening 7 shaped to receive a basket frame 8, which frame is provided with a peripheral wire 9 of such dimension that it will prevent the frame from slipping through the opening beyond a predetermined point.

A secondary base structure is supported on the above described bottom or primary base structure and this secondary base structure 50 comprises an inverted pyramid formed with

four panels 10 having their edges turned as at 11 to lie parallel with the top plate 3 to permit the securing of the secondary base structure in position by bolts or otherwise to this top plate. The panels are preferably formed of separate sheets welded together at their edges and the top edges of the panels are turned upwardly to form an enclosing flange 12, within which is adapted to be seated the dispensing refrigerator 13.

55 Suitable castors 14 are secured at each corner of the base frame 1 to permit the easy shifting of the structure over the floor.

I claim as my invention:

1. A supporting stand for bottle cooling receptacles comprising a pyramidal base having a rectangular base frame, four upwardly extending inwardly converging corner posts, means for connecting said corner posts together at their tops, panel plates secured to said corner posts and an inverted pyramidal support mounted on the tops of said corner posts.

60 2. A supporting stand for bottle cooling receptacles comprising a rectangular bottom frame, upwardly extending inwardly converging corner posts secured to said frame, a top plate connecting said corner posts at their tops, a plurality of panel members all formed from a single sheet of material secured to said corner posts, and an inverted pyramidal support mounted on said top plate.

65 3. A supporting stand for bottle cooling receptacles comprising a rectangular bottom frame, upwardly extending inwardly converging corner posts secured to said frame, a top plate connected to the tops of said posts, an inverted pyramidal support comprising side panels having their lower edges turned and secured to said top plate and having their upper edges upturned to form a peripheral flange.

70 In witness whereof, I CHESTER A. FRICK have hereunto set my hand at Indianapolis, Indiana, this 2nd day of May, A. D. one thousand nine hundred and thirty.

CHESTER A. FRICK.
